INVENTOR,

Emil W. S. Gay

UNITED STATES PATENT OFFICE.

EMIL W. S. GAY, OF ROXBURY, MASSACHUSETTS.

STRING-FASTENER.

1,330,256.

Specification of Letters Patent. Patented Feb. 10, 1920.

Application filed May 21, 1917, Serial No. 169,959. Renewed August 14, 1919. Serial No. 317,589.

To all whom it may concern:

Be it known that I, EMIL W. S. GAY, a citizen of the United States, residing at Roxbury, in the county of Suffolk, in the State 5 of Massachusetts, have invented certain new and useful Improvements in String-Fasteners, of which the following is a specification, reference being had to the accompanying drawings.

10 The object of this invention is to provide simple and effective means for fastening strings, cords, and the like, around bundles and more particularly for fastening the otherwise free end portion of a shoe string; 15 the operation of my said fastener being such that a single lacing may be used and the tying and untying of knots is entirely avoided.

Briefly described my invention comprises 20 a small clamp which is secured to the end of the string, forming in effect a tip for said string, and a spring clamp operating as a receiver for a bight of the string as well as for the tip, the construction and operation 25 of the co-acting parts being such that when the string has been drawn taut around a bundle, or through the eyelets of the shoe, as the case may be, the string is locked in its strained or taut position, and this desirable result is accomplished instantly by 30 simply wedging the tip into the clamping receiver.

In order to explain my invention clearly I have provided the annexed drawings, in 35 which Figures 1 to 9 both inclusive, illustrate one embodiment of my improved construction and Figs. 10 to 19 both inclusive, illustrate another and preferred form of my said invention. Fig. 1 is a longitudinal, sectional view of what I term the spring clamp receiver member of my said fastener having seated therein the tip member. Fig. 2 is a side view of said receiver, Fig. 3 is a top view and Fig. 4 is an underside view of 40 the same. In Fig. 5 I have illustrated the tip member complete and in Figs. 6, 7 and 45 8 I have shown the three parts of the said tip separated; Fig. 7 being in central, longitudinal section. Fig. 9 is an end view of 50 the tip section of Fig. 8.

Fig. 10 is a side elevation of my preferred form of receiver and Fig. 11 is an end view of the same. Fig. 12 is a plan view of the receiver of Fig. 10 and Fig. 13 is a central, 55 longitudinal, sectional view of the same.

Fig. 14 is a transverse, sectional view taken

on the line 14—14 of said Fig. 13. In Fig. 15 I have illustrated the receiver in section, as in Fig. 13, and have shown another form of tip seated in said receiver. 60

Fig. 16 illustrates, by a partial side view the said tip, the string clamping ferrule member being shown in section.

Fig. 17 is a side view of the metal tip proper. 65

Figs. 18 and 19 are relatively enlarged views of the clamping ferrule, Fig. 18 showing the same in longitudinal section and Fig. 19 showing particularly the milled circumferential exterior of the said ferrule. 70

Referring to these drawings the numeral 25 indicates a receiver formed of resilient sheet material having upturned sides 26—27 which may serve to clasp a metal tip 28, as seen in Fig. 1 of the drawings. The flat 75 end portions of the receiver are perforated, as here illustrated, in order that the receiver may be stitched or eyeleted, to the upper of a shoe. The tip 28 is formed in its mid portion as a truncated cone 28^a which 80 (when the tip and receiver are assembled) lies in an opening 29 in the bottom plate of the receiver, the base of the cone providing an offset shoulder which prevents the accidental separation of the tip and receiver. 85 The tip is formed of three separable members to wit the tip proper 28, the herein truncated cone member 28^a and the string-clamping ferrule member 30. The cone 28^a is bored and tapped to receive at one of its 90 ends the tip member which is threaded exteriorly as at 28^b and to receive at its other end the exteriorly threaded end of the ferrule 30, and the tip member 28 is also formed with a pointed inner end 28^c which 95 extends through the cone into the ferrule when the several parts are assembled.

When the tip thus described is to be attached to the end of a string as, for example, to the end of a shoe lacing, the ferrule 100 30 is first screwed into the cone 28^a and the end of the lacing is tucked into the ferrule until the ferrule is practically filled with the lacing. The tip member is then screwed into the cone until its pointed end portion 105 28^c engages and is forced into the soft material of the lacing, resulting in firmly wedging and clamping the lacing in the ferrule, as will perhaps be better understood if reference is made to Fig. 16 of the drawings. 110

In Figs. 12 to 19 the device illustrated

differs but little from that which I have just described. The receiver, however, is formed with indents 31 which, in effect provide ribs which coöperate with curvilinear 5 or ball-like enlargements 32—33 on the tip member.

Said tip member, as seen in Figs. 15, 16 and 17 is formed of two parts only instead of three as I have described in connection 10 with Figs. 1 and 5 but the operation of the complete device to wit the receiver and the co-acting tip, is the same in both forms of my invention.

In operating the said device the tip is secured to the end of the lacing as described. 15 After the string has been laced up (assuming that the device is being used with a shoe lacing) the end portion of the string is carried around the ankle of the wearer and 20 laid in the bottom of the receiver 25, the said receiver being secured to the upper of the shoe. The tip 28 is then forced endwise into the receiver until the base of the cone enters the opening, 29 or until the balls 25 32—33 pass the indents 31, as the case may be. This action not only clamps the tip in place in the receiver but at the same time, clamps the bight of the string, which lays

along the bottom of the receiver, firmly in place.

Thus by the aid of my described device I am able to readily secure the string end without having to knot the string as is now commonly done.

Obviously my invention is not limited in 35 all details to the embodiments of the invention herein shown, but may be varied within the scope of the following claims.

Having thus described my invention, I claim as new and wish to secure by Letters 40 Patent:—

1. The improved tip for shoe laces consisting of an interiorly threaded tube, and an exteriorly threaded double pointed tip member adapted to be screwed into said 45 tube.

2. In combination with a spring clasp, a tip for shoe laces; said tip consisting of an interiorly threaded tube member and an exteriorly threaded double pointed tip member formed with enlargements adapted to be wedged in said spring clasp. 50

3. A shoe lace tip comprising a lace receiving member, and a double pointed tip member adapted to lock the lace end thereto. 55

EMIL W. S. GAY.
